UNITED STATES PATENT OFFICE.

JOHN P. MACLEAR, OF PHILADELPHIA, PENNSYLVANIA, ASSIGNOR TO
ROBERT M. GREEN & SONS, OF SAME PLACE.

VALVE MECHANISM FOR SIPHON-VALVES OR DRAFT-TUBES.

SPECIFICATION forming part of Letters Patent No. 678,841, dated July 16, 1901.

Application filed December 31, 1900. Serial No. 41,633. (No model.)

To all whom it may concern:

Be it known that I, JOHN P. MACLEAR, a citizen of the United States, residing in Philadelphia, Pennsylvania, have invented certain Improvements in Valve Mechanism for Siphon-Valves or Draft-Tubes, of which the following is a specification.

My invention consists of an improved valve structure designed particularly for use in filling siphon-bottles.

My improved apparatus comprises means for packing the siphon-nozzle as the valve for admitting the fluid under pressure to said siphon is opened. I may also use the apparatus as a draft-arm, so that the liquid under pressure may be drawn off into a glass or other receptacle.

My invention is fully illustrated in the accompanying drawings, in which—

Figure 1 is a sectional plan view of one form of duplex apparatus, one end of the same carrying a draft-tube and the other end adapted to receive the nozzle of a siphon. Fig. 2 is a similar sectional view showing a siphon-nozzle connected therewith, one of the valves opened for the admission of the liquid under pressure, and the siphon-nozzle packed so that no leakage will occur during the passage of said liquid to the siphon. Fig. 3 is a sectional view of the form of the apparatus in which a single valve is used, such apparatus being shown in a vertical position and adapted to be mounted upon a counter or drinking-bar. Fig. 4 is a sectional front elevation of another form of the duplex apparatus in which two distinct casings are employed with single valves arranged in each casing. Fig. 5 is a side view, partly in section, of the form of duplex apparatus shown in Fig. 4; and Fig. 6 is a modification of the form of apparatus shown in Figs. 1 and 2 in which a movable casing is employed instead of the movable valve-plug.

The apparatus forming the subject of my invention in its duplex form is particularly applicable for use in saloons, cafés, or other places where liquid refreshment is dispensed, and when used in saloons the apparatus is preferably arranged at the back of the bar and may take the place of one of the usual beer-spigots.

The structure shown in Fig. 3 is particu-

larly applicable for counter use and may be used for filling a siphon or with the addition of a detachable draft-tube for drawing off the liquid under pressure into an ordinary glass tumbler or other suitable receptacle.

In the drawings herewith, in Figs. 1 and 2, 1 represents a tubular valve-chest having a pipe extension 2 connected therewith, the latter adapted to pass through the usual slate partition 3 at the rear of the bar and communicating with the tank or other receptacle containing the liquid under pressure. Arranged within the tubular valve-chest are the valves 4, controlling the outlet of the liquid under pressure, said valves having hollow stems 5, adapted to suitable openings in the tubular valve-chest. One end of the tubular valve-chest is closed by a screw-plug 6, and said plug is provided with an opening for the stem of one of the valves 4. Each valve is provided with a gasket 7, made of any suitable material, and these valves are held to their seats 8 by means of the coiled spring 9. One of said seats 8 is formed on the solid portion of the tubular valve-chest, while the other is carried by the screw-plug 6. Each of the valve-stems 5 is ported at 10, providing for the passage of the liquid when said valves are open, such ports including cross-passages and openings in line with the stem connecting said cross-passages. The ends of the valve-stems 5 are reduced at 11, forming seats for the plates 12, and compressible bushings 13, composed, preferably, of rubber, are interposed between said plates 12 and the ends of the inclosing sleeve or casing 14. The sleeve or casing 14 is capable of endwise movement on the tubular valve-chest, whereby the bushings 13 may be compressed between the ends of the same and the tubular valve-chest, the valves 4 being opened by such operation. To effect the movement of the sleeve 14, the latter is provided with a yoke-piece 15, to which a handle 16 is pivoted at 17. This handle is provided with hooked ends 18, adapted to pass through openings 19 in the sleeve or casing 14 and engage the abrupt shoulders of depressions 20, cut in the tubular valve-chest. Movement of the handle 16 in either direction will impart movement to the sleeve or casing in the same direction, the latter moving on the tubular valve-chest. The bushings 13

have a central opening 21 in line with the openings of the sleeve or casing 14, and the nozzle 22 of a siphon is adapted to be inserted in one of said openings, as shown in Fig. 2. 5 The opposite end of the sleeve or casing has a threaded projection 23, adapted to receive a draft-tube 24, the latter being threaded to correspond with the threaded portion of the projection 23, but having a plain portion to 10 enter the opening in the bushing. The end of the sleeve or casing is closed by a screw-plug 25, which has depressions 26 for the reception of the prongs of a suitable key to turn said screw-plug into place. The screw-plug 15 6 of the tubular valve-chest is also recessed at 27, so that it may be turned into place by the same tool used for turning the screw-plug 25.

In Fig. 2 of the drawings I have shown a 20 siphon in position to be filled with the liquid under pressure. The nozzle 22 of said siphon is fitted into the opening in the end of the sleeve or casing and enters the opening 21 of the bushing 13, these parts being of such size 25 that an initial close fit is provided for. The valve of the siphon is now opened and kept open while the siphon is filling. By moving the handle 16 in the direction shown in Fig. 2 the casing will be moved in the same direction, and the bushing 13 will be compressed between the end of the casing and the plate 12, carried by the stem of the valve, packing the end of the siphon-nozzle. As the bushing is compressed its greatest pressure is exerted upon the plate 12, carried by the valve-stem, and the valve is opened, the gasket 7, carried by the same, being moved away from the seat 8, and the port 10 is open for the admission of the liquid under pressure.

40 In filling siphons in the manner heretofore practiced great difficulty has been experienced in displacing the air as the liquid enters, it being necessary to remove them frequently from the filling apparatus, invert 45 them, so that the inner filling and discharge tube is above the line of liquid therein, and then open the valve of the siphon and permit the discharge of the air, a process known as "snifting." With my structure, however, 50 this snifting operation may be effected without removing the siphon from the casing 14.

This operation is as follows: The siphon to be filled is held in the inverted position with the end of its internal tube at the highest 55 point, and its nozzle 22 is then inserted in the opening 21 of the bushing 13. By maintaining the siphon-valve open all the time and alternately opening and closing the valve of the filling device, the bushing being compressed 60 to pack the siphon-nozzle and released simultaneously with the opening and closing of the valve, air is permitted to escape during the filling operation and the snifting accomplished without removing the siphon from the 65 device until it has been entirely filled with the liquid under pressure.

In Fig. 3 I have shown a form of the apparatus adapted to carry a loose draft-tube 24^a and having a single valve 4^a. This structure is practically the same as that shown in Figs. 1 and 2, except that it has a single valve and is arranged in a vertical instead of a horizontal position. The tubular valve-chest 1^a has the outlet-pipe 2^a from the source of supply screwed into the same, and the valve 4^a is 70 maintained against its seat by means of a spring 9^a, interposed between the end of said pipe 2^a and the valve 4^a. The tubular valve-chest has an annular depression 20^a, and hinged to the sleeve or casing at 17^a is a handle 16^a, having a projection 18^a, adapted to pass through an opening 19^a in the sleeve or casing and engage the abrupt shoulder formed by the annular depression 20^a. Downward movement of the handle 16^a will move the 80 casing 14^a, and the parts will be operated in the same manner as has been described with reference to Figs. 1 and 2.

In Figs. 4 and 5 I have shown a modified form of the duplex structure, in which the 90 tubular valve-chest 1^b is formed integral with the supply-pipe 2^b and has vertically-arranged members in which the valves 4^b are arranged. In this structure separate sleeves or casings 14^b surround said vertical members of the tubular valve-chest, and the valves are held in place by springs 9^b, the latter being retained by the screw-plugs 6^b, which close the ends of the vertical members. The handle 16^b is pivoted at 17^b to a yoke-piece 15^b, carried by 100 the supply-pipe 2^b, and has arms 18^b, the ends of which are adapted to engage pins 28, carried by the casings 14^b. The casings are slotted at 19^b for the passage of these arms 18^b. The ends of the casings are closed by 105 screw-plugs 25^b, and these screw-plugs are so shaped that they may be readily turned into place. This structure is adapted for use as a draft-arm or for filling a siphon. For the latter purpose the compressible bushing 13^b is carried in one of the casings. For the draft-arm, however, such bushing is not necessary, and in place of the same I prefer to use a section of metallic tubing 29, so that there will be a positive opening of the valve when the 115 casing is raised. In some instances it may not be necessary to insert the draft-tube, as the discharge is downward and is usually directed into a glass tumbler or other suitable receptacle.

In Fig. 6 I have shown a modification of the duplex form of the apparatus shown in Figs. 1 and 2, in which the tubular valve-chest is adapted to be moved within the sleeve or casing 14^c instead of having the sleeve 125 movable. In this form of the structure the tubular valve-chest 1^c is made in two parts, which are threaded together at 30, and an opening 31 is provided at such threaded portion for the passage of the liquid from 130 the supply-pipe 2^c. In this form of apparatus also the pipe 2^c is made integral with

the casing 14^c. Either end of this structure is adapted to receive the nozzle of a siphon or the end of a loose draft-tube, as may be desired. In this form of structure provision should be made for packing the valve-chest 1^c within the sleeve or casing 14^c, and I have shown packing 32 arranged within annular recesses in the surface of said valve-chest. This structure is provided with the valves, bushings, plates, &c., and the whole operated by the handle 16^c in the same manner as the device shown in Figs. 1 and 2.

Having thus described my invention, I claim and desire to secure by Letters Patent—

1. A structure of the character described comprising a valved member providing for the inlet and passage of liquid under pressure, means for operating the same, and means for preventing leakage of such liquid during its passage from said member to a closed receptacle comprising a compressible bushing surrounding the tube leading to said receptacle, and means for compressing the bushing said bushing being automatically compressed simultaneously with the operation of the valved member.

2. The combination in a structure of the character described, of a casing having an opening adapted to receive a siphon-nozzle or similar structure, a compressible bushing carried by said casing and surrounding the siphon-nozzle and means for compressing said bushing.

3. The combination in a structure of the character described, of a casing having an opening adapted to receive a siphon-nozzle or similar structure, a compressible bushing carried by said casing and surrounding the siphon-nozzle, a valve carried by said casing, and means for compressing the bushing and opening the valve at one operation.

4. The combination in a structure of the character described, of a casing having an opening adapted to receive a siphon-nozzle or similar structure, a compressible bushing carried by said casing and surrounding the siphon-nozzle, a valve carried by said casing in line with the siphon-nozzle, and means for compressing the bushing and opening the valve simultaneously.

5. The combination in a structure of the character described, of the casing, a tubular valve-chest therein, one of said members being movable with respect to the other, a valve carried by said valve-chest, a bushing interposed between the end of the casing and the valve, said bushing having an opening to receive a pipe or tube, and means for compressing said bushing.

6. The combination in a structure of the character described, of the casing, a tubular valve-chest therein, one of said members being movable with respect to the other, a valve carried by said valve-chest, a bushing interposed between the end of the casing and the

valve, said bushing having an opening to receive a pipe or tube, and means for compressing said bushing around the pipe or tube, the extra force exerted by said bushing under compression serving to open the valve. 70

7. The combination in a structure of the character described, of the casing, a tubular valve-chest therein, one of said members being movable with respect to the other, a valve carried by the valve-chest, means for holding said valve to its seat, a bushing interposed between the end of the casing and the valve, said bushing adapted to receive a pipe or tube, and means for simultaneously opening the valve and compressing the bushing against a tube inserted therein. 75

8. The combination in a structure of the character described, of the casing, a tubular valve-chest therein, one of said members being movable with respect to the other, a plurality of valves carried by said valve-chest, means for holding these valves to their seats, bushings interposed between the ends of the casings and the ends of the valves, said bushings adapted to receive pipes or tubes and means for moving said valves, the movement of the latter compressing one of said bushings so as to pack a tube inserted therein, 95 substantially as described.

9. The combination in a structure of the character described, of the casing, a tubular valve-chest therein, one of said members being movable with respect to the other, a plurality of valves carried by said valve-chest, means for holding said valves to their seats, bushings interposed between the ends of the casing and the spindles of said valves, said bushings adapted to receive pipes or tubes, 105 and means for moving the valve-chest or the casing whereby either one of said valves will be opened, such movement compressing one of said bushings so as to pack the tube and open the valve simultaneously. 110

10. The combination in a structure of the character described, of a casing, a valve-chest therein, one of said members being movable with respect to the other, a valve carried by said valve-chest, said valve having a hollow stem and passages communicating therewith, the end of said valve-stem being reduced, a plate fitting the reduced end of said stem, a bushing interposed between said plate and the end of the casing, said bushing having an opening in line with the hollow valve-stem and adapted to receive a pipe or tube, and a lever in operative engagement with the casing and the valve-chest whereby one of said members may be moved, such action compressing the bushing and opening the valve, 125 substantially as described.

11. The combination in a structure of the character described, of the movable casing, a fixed valve-chest located therein, a valve carried by said valve-chest, a spring for holding said valve to its seat, a compressible bush-

ing interposed between the valve and the end of the casing, and a handle pivoted to said casing and having a portion adapted to engage the valve-chest so that pressure on said handle will move the casing and compress the bushing, substantially as described.

5 In testimony whereof I have signed my

name to this specification in the presence of two subscribing witnesses.
